UNITED STATES PATENT OFFICE.

EMILIO GARCIA, OF BETHLEHEM, PENNSYLVANIA

AEROPLANE.

Application filed January 25, 1924. Serial No. 688,457.

To all whom it may concern:

Be it known that I, EMILIO GARCIA, a citizen of the United States, residing at Bethlehem, in the county of Northampton and State of Pennsylvania, have invented certain new and useful Improvements in Aeroplanes, of which the following is a specification.

This invention relates to certain new and useful improvements in aeroplanes, and has particular reference to aeroplane propulsion.

The primary object of the invention is to provide an improved form of propulsion mechanism for aeroplanes, by means of which the aeroplane may be caused to travel forwardly or ascend in a substantially vertical direction or at any inclination between the horizontal and vertical at will.

Another object of the invention is to provide an aeroplane with propulsion mechanisms characterized as specified above and embodying the desired qualities of simplicity and durability of construction, as well as efficiency in operation.

Briefly described, the invention pertains to bi-planes embodying a fuselage with pairs of superposed planes or wings extending from opposite sides of the forward end portion thereof, horizontal transversely disposed paddle wheel propellers mounted between the pairs of wings or planes, and means disposed between the wings of each pair and in front of the adjacent propeller for causing the latter to only exert a propelling force of noticeable effect in a direction to cause travelling of an aeroplane in an upward or forward direction, and means for shifting said planes or wings from their normal horizontal superimposed position to a vertical position with the planes or wings of each pair disposed one in advance of each other.

Other objects will appear as the nature of the invention is better understood, and the same consists in the novel form, combination, and arrangement of parts hereinafter more fully described, shown in the accompanying drawings and claimed.

In the drawings, wherein like reference characters indicate corresponding parts throughout the several views:

Figure 1 is a side elevational view of an aeroplane constructed in accordance with

the present invention, and with the planes or wings in their normal horizontal position.

Figure 2 is a view similar to Figure 1 with the planes or wings vertically disposed.

Figure 3 is a top plan view of the device shown in Figure 1.

Figure 4 is a fragmentary sectional view taken upon the line 4-4 of Figure 1.

Figure 5 is a view similar to Figure 4, but taken in a vertical plane of section, and

Figure 6 is a somewhat diagrammatic perspective view illustrating modifications of certain parts of the invention.

Referring more in detail to the drawings, the present aeroplane embodies an elongated body or fuselage 5 of any well known or preferred construction and provided at its rear end with the usual horizontal and vertical rudders 6 and 7 respectively adapted for controlling the course of the aeroplane in the usual general well known manner, the fuselage being also provided with the usual landing gear structure as at 8 and 9.

Journalled in and projecting outwardly beyond opposite sides of the forward end of the fuselage 5 is a horizontal propeller shaft 10 upon the projecting ends of which are fixed conventional propellers of the paddle wheel type embodying flat radial blades 11. Suitably journalled in and projecting through opposite sides of the fuselage 5 are sleeves 12 within which the propeller shaft 10 is rotatably disposed, and which sleeves are rotatable about said shaft 10. Rigid with the outer ends of the sleeves 12 and adjacent the outer surfaces of the sides of the fuselage 5 are frames 13 which rigidly connect the adjacent rigid ends of the adjacent pair of planes or wings 14, and each pair of wings 14 is rigidly connected at the outer end thereof by means of similar frames 13a that are rotatably disposed upon the outer ends of the shaft 10. A rigidly connected pair of planes or wings is thus mounted for rotation about the axis of the shaft 10 at each side of the forward end portion of the fuselage 5 so that said pairs of wings may be disposed in a vertical position as shown in Figure 2, or in a normal horizontal position as shown in Figure 1, as well as at any inclined position between the horizontal and vertical for determining the course of the aeroplane in a manner which will presently become apparent.

The adjacent inner ends of the sleeves 12

are connected by a crank 15 to which is attached a rearwardly extending operating link or rod 16 that is in turn connected with a suitable control lever 17 disposed within the driver's compartment 18 of the fuselage. Any suitable means, such as a segment rack and latch may be provided for maintaining the lever 17 in any position to which it is swung, and it is thus apparent that by swinging the lever 17, the wings 14 may be simultaneously moved to the desired inclined, horizontal, or vertical position with the wings or planes maintained in their parallel relation.

Various means may be provided for driving the shaft 10, such as a motor 19 mounted within the forward end of the fuselage 5 and operatively connected to the shaft 10 within the fuselage by means of a bevelled gear indicated at 20, and a sprocket gearing indicated at 21, the sprocket gearing including a sprocket wheel 22 fixed upon the shaft 10 between the adjacent ends of the sleeves 12 and co-incident with the crank 15. It is obvious that clutch means may be provided for disconnecting the engine from the shaft 10 as is well known in the art, and that is therefore not shown.

Under ordinary circumstances, the use of paddle wheel propellers in the manner shown would be ineffective due to the same exerting propelling force to substantially the same degree in a rearward direction as in a forward direction. In order to overcome this difficulty and to insure action of the propellers to cause only forward and upward movement of the aeroplane, I rigidly connect the forward edge portion of the wings 14 of each pair by means of vertical and preferably forwardly curved frame bars 23 which rigidly support a plurality of spaced superimposed horizontal slats 24 which are horizontally disposed and tilted about their longitudinal axes or about axes perpendicular to the longitudinal axis of the aeroplane. The slats 24 are preferably tilted forwardly and downwardly as shown, so that the propellers are adapted to be driven in an anti-clockwise direction as indicated by the arrows *a* shown in Figures 1 and 2. The effect of these slats is to induce the air to travel with the propeller blades at the forward side of the shaft 10 and to only be delivered from the blades in a rearward direction between the rear edges of the planes or wings 14. Air entering between the slats 24 will be directed by the latter in an upward direction above the shaft 10 so as to act upon the blades as they pass to a position above the shaft 10, thus offering little resistance to the forward movement of the blades as they pass beneath the level of the shaft 10 and in a forward direction.

As shown in Figure 6, the upper wing 14^a of each pair may be constructed to pro-

vide a longitudinal pocket or cavity as at 25 within which the blades of the propellers pass during rotation of the latter and the forward edge portions of the lower wings 14^b may be upwardly curved so as to induce the air to travel with the blades and to pass against the latter only as they are positioned above the level of the propeller shaft. By thus forming or constructing the respective wings of each pair and associating the same with the propellers in this manner, the slats 24 will be materially assisted in performing the above ascribed function for rendering the use of the paddle wheel propeller practical, the slats 24 being omitted from this Figure 6, for sake of clearness.

In operation, assuming that it is desired to ascend substantially vertically from the ground, the lever 17 is manipulated so as to cause rotation of the sleeve 12 and thereby swing the wings or planes 14 to the vertical position as illustrated in Figure 2. The motor 19 is then started in operation, so as to cause the propellers to be driven in the direction of the arrows *a*, and when these propellers attain a predetermined speed of rotation they will cause a lifting force to be exerted for causing the aeroplane to rise in the air. Obviously, ascension may be obtained by disposing the planes or wings 14 substantially horizontally as shown in Figure 1, and manipulating the rudders 6 and 7 in the usual well known manner during the operation of the propellers. A gradual ascension may be facilitated, also, by disposing the planes or wings 14 at a forward and upward inclination.

From the foregoing description, it is believed that the construction and operation as well as the advantages of the present invention will be readily understood and appreciated by those skilled in the art.

What I claim as new is:

1. In an aeroplane, a fuselage having transversely and horizontally disposed paddle wheel propellers at opposite sides thereof, pairs of normally superimposed horizontal planes disposed at opposite sides of the fuselage, the planes of each pair being respectively disposed above and below the adjacent propeller, means for mounting said planes upon the fuselage for movement in a circular path concentric with the axis of the propellers, and means for moving said planes.

2. In an aeroplane, a fuselage having transversely and horizontally disposed paddle wheel propellers at opposite sides thereof, pairs of normally superimposed horizontal planes disposed at opposite sides of the fuselage, the planes of each pair being respectively disposed above and below the adjacent propeller, means for mounting said planes upon the fuselage for movement in a circular path concentric with the axis of the propellers.

propellers, and means for moving said planes, and means disposed in front of the propellers and between the forward edges of the planes of each pair for diverting the air upwardly and rearwardly.

3. In an aeroplane, a fuselage having transversely and horizontally disposed paddle wheel propellers at opposite sides thereof, pairs of normally superimposed horizontal planes disposed at opposite sides of the fuselage, the planes of each pair being respectively disposed above and below the adjacent propeller, means for mounting said planes upon the fuselage for movement in a circular path concentric with the axis of the propellers, means for moving said planes, means disposed in front of the propellers and between the forward edges of the planes of each pair for diverting the air upwardly and rearwardly, said last named means including transverse horizontal slats disposed in spaced superimposed relation and tilted above their longitudinal axes.

4. In an aeroplane, a fuselage having transversely and horizontally disposed paddle wheel propellers at opposite sides thereof, pairs of normally superimposed horizontal planes disposed at opposite sides of the fuselage, the planes of each pair being respectively disposed above and below the adjacent propeller, means for mounting said planes upon the fuselage for movement in a circular path concentric with the axis of the propellers, means for moving said planes, means disposed in front of the propellers and between the forward edges of the planes of each pair for diverting the air upwardly and rearwardly, said propellers having a common drive shaft, and a mounting means for the plane embodying frames rigidly connecting the frames of each pair and journaled upon the propeller shaft.

In testimony whereof I affix my signature.

EMILIO GARCIA.
